UNITED STATES PATENT OFFICE.

EMORY CURTIS HISCOCK, OF BROOKLYN, NEW YORK, ASSIGNOR TO EDWARD B. JORDAN AND EDWARD B. JORDAN, JR., OF BROOKLYN, NEW YORK.

TALKING-MACHINE CABINET.

Application filed September 12, 1919. Serial No. 323,389.

To all whom it may concern:

Be it known that I, EMORY CURTIS HISCOCK, a citizen of the United States, and a resident of Brooklyn, in the county of Kings and State of New York, have invented certain new and useful Improvements in Talking-Machine Cabinets, of which the following is a specification.

This invention relates to a talking machine cabinet.

In the usual method of manufacture of talking machine cabinets the parts are made and permanently built up into an assembled cabinet and then the cabinet is finished by staining, varnishing, or painting, rubbing down, etc. Due to the interstices, corners, and bulk in handling the finishing is expensive and the shelves and interior cannot be rubbed down but are generally only stained by the artisan using a swab or long handled brush as it is impossible to give the interior and the shelves the same finish as the exterior by reason of the lack of space. In this invention the parts are not only separately made but they are also separately finished. One of the objects of this invention is a method of manufacturing talking machine cabinets whereby the parts are separately made and separately finished at less cost than built up cabinets and adapted to quantity production.

In addition to enabling a better method of manufacture, a cabinet capable of being readily assembled or disassembled permits of a saving in storage space and freight charges as well as a saving of cost and greater ease in crating as it can be shipped knock-down. Crated and shipped knock-down there is less chance of injury. Another object of this invention is the construction of a talking machine cabinet capable of being readily assembled or taken apart by a simple locking or unlocking of the parts comprising the cabinet.

Still another object is the construction of a knock-down cabinet with interlocking parts such that when assembled they form a rigid cabinet to all appearances and purposes the same as a built up one.

Referring to the accompanying drawings and to the various views and reference signs appearing thereon:

Figure 1 is a side, sectional view of a cabinet looking in the direction of the arrows along line 1, 1, Fig. 3; Fig. 2 is a sec-

tional view of a cabinet looking from back to front in the direction of the arrows on line 2, 2, Fig. 3; Fig. 3 is a sectional plan view; Fig. 4, is a detail sectional view showing the top locking means; Fig. 5 is a detail section showing retaining screws; Fig. 6 is a detail view of latch on bottom shelf; Fig. 7 is a front view, parts broken out, of a modified form; Fig. 8 is a plan view of the modified form; Fig. 9 is a modified form of shelf and partition arrangement; and Fig. 10 is a detail view of the locking means for the modified form of shelf and partition arrangement; Fig. 11 is a detail view of a modified form of interlocking means; Fig. 12 is a detail view of section 12, 12, Fig. 11 looking in the direction of the arrows of the modified form of interlocking means.

Referring to Figs. 1, 2 and 3, 1, 1 are the front posts and 2, 2 are the rear posts. The posts 1 and 2 have grooves lengthwise thereof and having supporting pins 8 spaced at regular intervals therein. The side panels 4 and 6 have cut out portions 9 substantially L-shaped and regularly spaced to conform to the spacing of the pins 8 and adapted to lock with the pins when the panels are shoved into the grooves of the posts and then slightly down. The bottom 11 is tongue and groove supported by pieces 12 carried by panels 4 and 6. In the same manner shelves 14, 15, 16, 17, 18 and 19 are supported by pieces 12 fastened to panels 4 and 6 and locked in place by panels 3 and 5. Top 20 has a cover 21 hinged thereto. To the underside of top 20 is fastened the talking machine motor 22. Two L-shaped blocks 23, (Fig. 4) are screwed to the underside of the top 20 to be slide under and held by blocks 24 fastened to the rear panel 5 to lock the top 20 to the panels and posts. The side panels 4 and 6 carry blocks 25 to which the top 20 is secured by four holding screws 26, to permit moving the cabinet around without inadvertently unlocking the top 20 and perhaps displacing it. The compartment 27 containing the usual sounding horn is a separate unit and is removable, it fits snugly between the motor board 22 and shelf 19 and against the customary grilled sound opening plate 28 to lock it in place. The grilled opening 28 fits in a channel or way in cross piece 29 and is supported by cross piece 30. The doors 7, 7 are hinged to the posts 1, 1.

In the form shown in Figs. 1, 2 and 3 the

front and back panels and doors are permanently attached to posts 1, 1 and 2, 2 respectively and together constitute, in effect, the front and back panel units or panels, while 5 in the modified form shown in Figs. 7 and 8 the front and rear panels are separable from the posts 1, 1 and 2, 2 and interlock therewith in the same manner as the side panels. The doors 7, 7 are hinged to the front posts 10 1, 1 in the forms shown in Figs. 1, 2 and 3 and in the forms shown in Figs. 7 and 8 the doors 7, 7 are hinged to the front panel proper, i. e., member 3. In all other essential details the structure shown in Figs. 15 7 and 8 is the same as that shown in Figs. 1, 2 and 3.

Referring to Figs. 9 and 10, these views show a modified form or arrangement of removable shelves and partitions. Shelf 17 20 and piece 35 have dados 34 for partitions 33. Stop 36 prevents the record books from being inadvertently shoved in too far. Strips 31, and 37 lock the shelves and partitions in place in connection with the molding 32 25 which is tacked or nailed to shelf 17 after locking strips 31 are in place and fits snugly between them. Locking strips 31 have a close fit between the top and bottom shelves and behind the posts 1, 1, while strip 37 fits 30 snugly between strips 31 and between piece 35 and cross piece 38.

The assembly of the cabinet is quickly 35 and easily accomplished without the use of any tools except a screw driver for the two retaining screws for the top. The front panel 3 is interlocked with posts 1, 1; the side panels 4, 6 are then locked to posts 1, 1; the shelves 11 to 19 are then slid into their ways 12 and posts 2, 2 and the side panels 4 40 and 6 are locked. The hook 13 is hooked to its pin to prevent spreading and the dropping out of the shelves when the compartment 27 is inserted. The grill 28 and compartment 27 are inserted. Panel 5 is now 45 interlocked with posts 2, 2 to lock the parts together and in their place. Top 20 is put on and blocks 23 are caught under blocks 24 to lock the top to the cabinet proper and holding screws 26 are screwed down. The 50 cabinet is then assembled into a rigid unit.

The modified form of shelves and partitions could be used in built up cabinets as well as in the knock-down structure of this invention. The shelves 17 and 18 are slid 55 in, the partitions 33 are slid into dados 34 and locking strips 31 and 37 are inserted and molding 32 is nailed on.

The parts 33 can be used as shelves when 60 desired as they are adapted to be slid into guides 12. Record albums are not sold as part of the cabinet and hence the most convenient form for the owner in the case of loose records is to use the parts 33 as partitions, but later on the owner upon the purchase 65 of albums can change the partitions

into horizontal shelving which is then more convenient and desirable. The change is accomplished by removing the locking pieces 31, 37, sliding out the partitions 33 and sliding them into guides 12 and replacing the 70 locking pieces 31 and 37.

Other forms of interlocking means between the panels and the posts can be readily devised that are effective such as the form shown in Figs. 11 and 12 wherein the 75 pins 39 engage the pins 8 in the slot 40 in the posts. The shoulders 41 in co-operation with the wedging effect of the pins 39 and 8 hold the parts rigidly in interlocked relationship.

From the foregoing description it will be seen that I provide an extremely simple construction and arrangement of interlocking parts to form a knock-down cabinet that is strong and rigid. Such a form of construction lends itself to quantity production and the saving of much workshop and storage space. The simple parts can be cut out and made by machine and finished by machine at a lower manufacturing cost. The parts are dried in racks and occupy a very much less space than the completed cabinets would while drying. The parts can be packed in several crates as found convenient, a desirable feature in export shipping by reason 90 of the saving of freight and breakage. The removable horn can be separately packed to prevent injury.

The panels and other parts can be made 95 from veneer.

Having now set forth the object and nature of my invention and various arrangements embodying the principles thereof, what I claim as new and useful and of my own invention, and desire to secure by Letters Patent is:—

1. In a knock-down talking machine cabinet comprising separable sides, removable top, and removable shelves and partitions, means for interlocking the sides, means for locking the top to the sides and means for locking the removable shelves and partitions.

2. In a talking machine cabinet having removable shelves and removable partitions maintained between a pair of said shelves, means for adapting said partitions for use as additional shelves, locking strips engaging the edges of said partitions and shelves to prevent accidental withdrawal of the same, and means for holding said locking strips in position.

3. In a knock-down talking machine cabinet comprising separable sides, removable top, and removable shelves and partitions, means for interlocking the sides, means for locking the top to the sides, means for adapting said partitions for use as additional shelves, and means for locking the shelves and partitions.

4. In a knock-down talking machine cab-

- inet comprising four separable side panels, four posts, and a separable compartment for a sounding horn, means for interlocking said side panels with said posts, means for holding said compartment in position, and means for holding three side panels in locked position with the posts while the device is being assembled and before the fourth side panel is interlocked with said posts, to permit the insertion of said compartment.
5. In a knock-down talking machine cabinet comprising four separable side panels, four posts and a plurality of shelves, means for interlocking said side panels to said posts, and means carried by said shelves and by said panels for holding three of said side panels in interlocked relation with said posts to form a rigid structure while being assembled, before said fourth side panel is 10 interlocked in position.
6. In a knock-down talking machine cabinet, separable side panels, pin means for removably interlocking said side panels, and a horn compartment between the interlocked sides.
- 15 7. In a knock-down talking machine cabinet, separable side panels, a removable top, supporting pin means for interlocking said
- side panels, a horn compartment between the interlocked sides, and means for securing 20 said top to the interlocked sides.
8. In a knock-down talking machine cabinet, separable side panels, means for interlocking said side panels, a shelf held between the interlocked sides, and a horn compartment between the interlocked sides and supported by said shelf, said panels being 25 demountable by an upward and outward movement from said interlocking means.
9. In a knock-down talking machine cabinet, a plurality of posts, separable interlocked panels joining and fitting within a groove in said posts, supporting pins within each groove in the posts, the cooperating edges of the panels being provided with 30 means adapted to receive said pins and hold the panels in position at least partially by their weight, removable partitions inside said cabinet, a horn compartment within said interlocked panels, and means for securing 35 a cabinet top on said panels.

Signed at borough of Brooklyn, in the county of Kings and State of New York, this 8th day of September, A. D. 1919.

EMORY CURTIS HISCOCK.
